MEAT-BLOCK STRUCTURE

George L. Burger, Chicago, Ill.

Application December 9, 1948, Serial No. 64,341

1 Claim. (Cl. 146—215)

1

My invention relates generally to store fixtures and it more particularly concerns a meat-block structure.

The meat-block customarily used heretofore in butcher shops comprises a block of wood of laminated sections and having supporting legs received in generally vertically disposed openings in the bottom surface of the block. Initially, the working surface of prior blocks is spaced above the floor at a desired fixed working height. However, during use of the block, the working surface becomes rough and uneven and waste matter finds its way into such surface to a considerable depth even though the block be made of very hard wood such as maple or the like. Repeated dressing operations are required to restore the working surface to the desired flat and sanitary condition. In each such dressing operation, as distinguished from day-by-day cleaning, the working surface of the block is cut away to a substantial extent, for example two (2) inches, to insure the desired sanitary surface. Accordingly, with each dressing operation the height of the working surface of the block is lowered approximately two (2) inches, and the block becomes increasingly inconvenient for its intended use. In view of the relatively high replacement cost of such fixtures, many meat cutters or butchers prolong the use of their meat-block with great inconvenience to themselves or to their employees. In such prior blocks, the working surface may be dressed away to approximately the center of the block whereupon the block may be discarded. In certain instances, when the normal working part of the block has been used up, suitable leg openings have been drilled in the upper surface of the block, the legs have been removed from the bottom of the block, and the block inverted with the legs mounted in the openings in the upper side of the block. This not only provides an unsightly block but requires plugging of the former leg openings which are now at the top of the block, which, together with the drilling of the new leg openings, requires tedious and expensive operations to insure the proper, sanitary working surface. Also, in certain instances, the working height of prior blocks has been maintained by adding extensions to the legs, but that is unsightly and tends toward an unsanitary condition.

One of the objects of my invention is to provide an improved meat-block structure wherein the prior difficulties and inconveniences are eliminated.

Another object is to provide a meat-block which

2

will have its work surface disposed a fixed distance above the floor, irrespective of repeated dressings of the work surface of the block.

A further object is to provide an adjustable support for a reversible meat-block whereby the work surface of the block is maintained at substantially the same height in both normal and reversed conditions until the block is substantially completely worn out by surface dressing.

10 An additional object is to provide a meat-block structure of the foregoing character which is sanitary and has increased longevity.

A still further and more specific object is to provide a rectangularly-shaped, reversible meat-block with a supporting container of similar shape having shim elements therein to control the depth of entry of the block therein in either upright or reversed condition and a resilient seal element disposed between the side walls of the container and the side walls of the block to prevent the entry of meat particles, juices and other waste matter into the block container.

Other objects and advantages will become apparent as this description progresses and by reference to the appended drawings wherein—

25 Figure 1 is a front elevation view of a meat-block structure embodying my invention;

Fig. 2 is an enlarged and partial vertical sectional view of the structure illustrated in Fig. 1, showing the meat-block resting on shim elements supported in the block container; and

Fig. 3 is a perspective view of a shim element for the meat-block.

In carrying out my invention, I employ a butcher block made from hard wood such as high grade maple. I eliminate the use of supporting legs on the block per se. According to my invention, the block is supported by a metal container having metal legs integral therewith which support the container a fixed distance above the floor. The container is adapted to receive and support upon its bottom a variable number of height-maintaining support elements in stacked fashion. The upper and lower halves of the block are identical so that the block may be reversed. The lateral dimensions of the container are such that the block is not only telescopically and freely received therein but is spaced from each vertical side wall of the container an extent to allow the use of a removable seal element closely encircling the block and disposed between the spaced side walls of the container to effectively seal the container and provide a sanitary structure.

Referring to the drawings, the meat-block structure 10 (Fig. 1) includes a rectangularly-

shaped metal container 11 having four supporting legs 12 (one at each corner) permanently secured to the underside thereof by any suitable means, for example, by welding. The container 11 is open at the top and has a depth somewhat less than the depth or thickness of the meat-block to be received therein. The bottom of the container 11 is cut-away to provide a rectangularly-shaped, shelf-like bottom wall 13 encircling the container and to provide a central opening 14 permitting communication of the atmosphere with the interior bottom portion of the container for well-known sanitary reasons.

The container 11 is adapted to receive a meat-block 15 which is formed of a plurality of pieces of hard wood, for example maple, which are permanently held together by dowels or tie bolts 16 to form a substantially integral block. Block 16 is constructed in accordance with the customary dimensions for such block and is adapted to be freely received in the container 11 and to be spaced from each side wall of the container an extent to provide a space 17 encircling the vertical side walls of the block.

The meat-block 15 is supported in the container 11 with its top working surface 18 disposed at a convenient height above the floor and above the top of the container 11. The block support is adjustable in character and includes at least one shim element 19 preferably formed of wood with lateral dimensions approximating the lateral dimensions of the meat-block 15 so that it may be freely received in the container 11. The shim element 19 is further formed in the shape of a hollow square having an opening 20 therein for registration with the opening 14 in the bottom of the container. Each shim 19 has a vertical dimension of approximately two inches, which dimension has been found to be the extent that the block 15 is usually dressed to restore the desired working surface after the block has been used for a considerable period of time. It is understood that a two-inch dimension for the thickness of shim 19 is not critical and that shims having a thickness other than the two-inch thickness just mentioned may be used with equally satisfactory results. When the most convenient height has been determined for the working surface 18, an appropriate number of shim elements 19 are placed upon the bottom 13 of the container and the block 15 is placed in the container 11 upon the surface of the top shim 19.

Means are provided to effectively seal the structure against entry of waste matter between the block 15 and container 11. This means comprises a resilient seal element 21, formed preferably of rubber. The seal element 21 (Fig. 2) takes the shape of a continuous, rectangular band having a flat body portion 21a adapted to fit snugly between the upper part of the container 11 and the block 15 to provide a tight seal at that point. The seal element 21 is further provided at the top edge of its body portion 21a with an overhanging head portion 21b having an inner wall surface 21c adapted to seat snugly against the block 15 and an outer wall 21d extending downwardly and outwardly over and beyond the upper edge of the container 11. This effectively prevents entry of waste matter from the block into the container.

The use and adjustment of my meat-block structure will now be described. When the structure is originally installed for use, it is advisable to adjust the working surface of the

block 15 to the most convenient height for the user. For this reason, the height of the bottom wall 13 from the floor plus the thickness of the block 15 in its original condition may be slightly less than what has been found to be an average, convenient height for meat-block structures. The height of the working surface 18 is then adjusted to suit the convenience of the user by placing the required number of shim elements 19 in the container 11 to bring the working surface to a suitable height. One such adjusted height is illustrated in Fig. 1 wherein two shim elements 19 are shown in position in the container 11 to support the block 15 at the desired height. It is understood that a block may be supported in the container without the use of a shim in the first instance and the block will rest on the bottom surface 13 of the container with the working surface of the block projecting above the container top. However, after considerable use of the block, the working surface will become uneven and unsuitable for further use so as to require the regular dressing operation. To restore the usefulness of the structure, the top 25 of the block 15 may be dressed away by any suitable tool until the desired sanitary working surface is again provided on the top of the block. Each dressing operation usually reduces the block in thickness by approximately two inches and will lower the working surface relative to the floor by the amount dressed from the block. The block is then restored to its previous height relative to the floor, simply by placing a shim element 19 in the container and under the block each time that the block is dressed. Eventually, with repeated dressings, the top surface of the block approaches the tie bar elements 16 to preclude further dressing of that side of the block. However, when this condition prevails, the block 30 may be used further simply by removing it from the container 11 and reversing it in the container so that what was previously its top surface becomes the bottom or innermost surface located in the container and what previously was the bottom surface becomes the top or working surface, which surface may be repeatedly dressed as required until it approaches the tie bars 16. At this time, a new meat-block is substituted for the old block without change of the container. However, the old block is not discarded as it is especially useful as a slicing or cutting block 35 commonly used in butcher shops. After each dressing operation, an additional shim element 19 is placed in the container so that the working surface of the block always remains at a constant height in respect to the floor and in the most convenient position for the user of the structure.

Since the supporting legs 12 and the container 11 are formed of metal, they provide maximum durability and long life. The container may be painted or enameled to provide outer surfaces which may be easily cleaned and present a neat appearing store fixture. It may be used over and over indefinitely, though the meat-block may be renewed. The working surface of the structure may easily be maintained at the proper height for most convenient use. The cost of meat blocks is materially reduced, with increased sanitation. The resilient seal element 21 provides maximum sanitation and is easily removable to allow thorough internal cleaning of the structure, the addition of shim elements 19, or the reversal of the meat-block in the container.

I claim:

75 A meat-block structure comprising a fabricated

wood block of large thickness and uniform horizontal cross-section and with all surfaces free from substantial protuberances and indentations, an open topped, laterally closed, supporting container formed to receive said block telescopically and readily reversibly end for end through its open top with small uniform spacing of the container side walls from the side faces of said block and with the uppermost end of said block projecting above the side walls of said container, a variable number of shims in the form of open frames of a horizontal section outwardly conforming to the horizontal cross-section of said block, said container having, below said block and shims, a flange extending inwardly from its side walls at least far enough to support said frame shims within said container at the lower end thereof, whereby said block may be held in said container, either end uppermost, and with the uppermost end projecting above the sides of said container to an adjusted height determined by the number of said shims placed within the container beneath said block throughout a range equal to the usable thickness of said block, and a resilient sealing member encircling the block, 25 said sealing member having a sliding sealing fit on the block and having a portion entering snugly between the block and the inner surface of the

upper end portion of the container and having a lip portion overlying the upper end edge of the container to seal the upper end of the container in all vertically adjusted positions of the block within the container.
